Primary Examiner—Mitchell Siegel(74) *Attorney, Agent, or Firm*—Burns, Doane, Swecker & Mathis, L.L.P.**CLAIM**

The ornamental design for a portion of a golf putter head, as shown and described.

DESCRIPTION

FIG. 1 is a bottom plan view of a portion of a golf putter head showing my new design.

FIG. 2 is a left side elevational view thereof; the right side being a mirror image thereof.

FIG. 3 is a front elevational view thereof.

FIG. 4 is a rear elevational view thereof; and,

FIG. 5 is a bottom perspective view thereof.

The broken line showing of various portions of the golf putter head is for illustrative purposes only and forms no part of the claimed design.
